UNITED STATES PATENT OFFICE.

WILLIAM O. DAVIES, JR., AND ROBERT HUGHES, OF CHICAGO, ILLINOIS.

BELT-TIGHTENER.

SPECIFICATION forming part of Letters Patent No. 634,055, dated October 3, 1899.

Application filed May 28, 1898. Serial No. 682,083. (No model.)

To all whom it may concern:

Be it known that we, WILLIAM O. DAVIES, Jr., and ROBERT HUGHES, citizens of the United States, residing at Chicago, in the county of Cook and State of Illinois, have jointly invented certain new and useful Improvements in Belt-Tighteners; and we do hereby declare the following to be a description thereof sufficiently full, clear, and accurate to enable persons skilled in the art to make and use the same.

The object of our invention is the production of a device for drawing together the ends of a belt which shall be simple in construction, easily manipulated, cheap in first cost, durable, efficient in operation, adapted for application to belts in any position, and which shall possess other desirable features and characteristics.

Our invention consists in certain novelties of construction and in the combination and arrangements of parts and elements, one relative to another, as hereinafter specified, and pointed out in the claims.

The accompanying drawings illustrate the best of the several modes we have so far devised for the practical application of the principle of our invention.

Figure 1 is a perspective view of our improved belt-tightener, the members of each pair of clamping-bars being shown separated some distance each from the other. Figs. 2 and 3 illustrate opposite ends of a pair of clamping-bars, the upper bar having at one end a closed slot and at the other end an open slot. Fig. 4 shows the method of attaching the end of one of the movable bars to an operating-lever.

Referring to the views, the letters A A designate two ratchet-bars; B B, ends of the bars; C C, tapering slots in the ends; D D', upper and lower teeth on the ratchet-bars; E E, horizontal slots with closed ends in the body of each bar; E' E', perpendicular slots in the bars; F F, holes made in the ends of the ratchet-bars which communicate with the horizontal slots E E and the perpendicular slots E' E'.

G G are movable bars; H H, tapering slots at the ends; I I, perforated bearings at the opposite ends.

J J are operating-levers located in the slots E E; K K, upper pawls; L L, pins by which the pawls K K are pivoted to the lever; M M, the lower pawls; N N, weighted ends of the 55 pawls; O O, pins by which the pawls M M are pivoted to the levers at their lower ends; P P, pins which pivotally unite the movable bars G G to the operating-levers, the ends of the said pins projecting some distance and resting and adapted to travel in the horizontal slots E E of the ratchet-bars.

Q Q' are upper and lower clamping-bars arranged in pairs; R R, cut-away or beveled ends of the bars, adapting the said ends to 65 fit the tapering slots in the ratchet and movable bars so as to maintain each pair of the clamping-bars parallel, whatever their location in the slots; S S, closed slots in the upper bars; T T, open-ended slots in the upper bars, 70 which allow the upper bars to move endwise and the pairs of bars to be separated without removing the thumb-screws; U U, threaded perforations in the lower bars; V V, thumb-screws; W W, strengthening ribs or webs integral with the clamping-bars. 75

The method of using our belt-tightener is as follows: The movable bars G G are first drawn out as far as possible and the clamping-bars Q Q' moved so that the ends will occupy the widest parts of the slots in which they are located. Then the two ends of the belt are inserted between the clamping-bars at opposite extremities of the tightener and the thumb-screws revolved, compressing the 85 body of the belt between the bars. Finally, the operating-levers are reciprocated, causing the bars G G to move in a direction parallel with the ratchet-bars and at the same time to carry one end of the belt with them. 90 The slots C C and H H, within which the ends of the clamping-bars move, being of a tapering form, as shown, occasion a firmer grip of the said clamping-bars upon the belt as the tension of the belt is increased. Obviously 95 under these conditions the belt cannot slip between the bars.

From the foregoing it will be seen that we have produced an improved belt-tightener which is simple in construction, easily manipulated, and of great strength and light weight, which will draw the ends of a belt 100

together without the use of wrenches, threaded rods, or cranks and blocks of wood joined together by set-screws, which will grip the belt its full width, thereby advancing the 5 ends of the belt squarely, which is adapted to be used in connection with both horizontal and perpendicular belts and without removing them from the pulleys, which is so constructed that ample room is afforded for lacing or cementing the adjacent ends of the belt, which can be applied and operated by one person, which can readily be applied to any width or ply of belt, which will not cut or tear the belt, and which will not allow the belt to slip when being tightened whether the same is oily or not, as the more the levers are worked the tighter the clamps grip the belt.

While we have illustrated a specific construction in the drawings, we do not wish to be limited to the exact details of form or arrangement of the several parts, inasmuch as changes may be made without constituting a substantial departure. For instance, the bar 20 A may be of any form and made in one piece or of several pieces united, the parts B B may be integral with the bars A A or joined to them, the movable bars be differently located, and many other modifications be introduced at the will and choice of the manufacturer. 25 All colorable substitutions and alterations we shall regard as falling within the scope of our claims.

What we claim as new, and desire to secure 30 by Letters Patent, is—

1. The combination in a belt-tightener of ratchet-bars having tapering slots at the ends; movable bars having tapering slots at the ends; operating-levers with attached pawls 40 and pairs of clamping-bars adapted to fit the tapering slots in the ends of the ratchet-bars and movable bars; whereby the members of each pair of clamping-bars will be forced toward each other as they move in the direction of the small ends of the tapering slots; in substance as set forth.

2. The combination in a belt-tightener of the clamping-bars; the movable bars; the ratchet-bars; and the operating-levers having 50 pawls; the said movable bars being pivoted to the operating-levers by pins which project into horizontal slots in the ratchet-bars and are guided by said slots; in substance as set forth.

3. The combination in a belt-tightener of the ratchet-bars A, A, having ends B, B, with slots C, C, and upper and lower teeth D, D'; operating-levers J, J, with pawls; movable 55 bars G, G, having slots; and pairs of upper

and lower clamping-bars Q, Q'; in substance 60 as set forth.

4. The combination in a belt-tightener, constructed substantially as described, of pairs of clamping-bars each member of each pair of said bars being beveled at the ends and 65 bars having tapering slots to receive the ends of the clamping-bars; substantially as and for the purpose specified.

5. The combination with a belt-tightener, constructed substantially as described, of 70 movable bars G, G; operating-levers; and ratchet-bars having holes F F; the bars G G being attached to the levers and moving in the holes of the ratchet-bars; in substance as set forth.

6. The combination with a belt-tightener, constructed substantially as described, of operating-levers; and ratchet-bars having slots E and E'; the said levers being located within the slots E' and guided by suitable means 80 in slots E; in substance as set forth.

7. The combination in a belt-tightener of two main bars; two bars movable relative to the first-mentioned bars; operating-lever mechanisms attached to the movable bars and 85 guided by the main bars; and pairs of clamping-bars adapted to grip the ends of a belt, the ends of one pair of clamping-bars so engaging the movable bars that the end of the belt will be compressed between the clamping-bars with increased force as the belt is stretched; substantially as and for the purpose set forth.

8. The herein-described belt-tightener, consisting of two ratchet-bars having teeth on 95 their upper and lower sides; two operating-levers, each having upper and lower pawls, said levers being combined with and guided by the said ratchet-bars; two movable bars united at their ends to the operating-levers; 100 and pairs of clamping-bars located at the ends of the device and secured to the ratchet and movable bars; in substance as and for the purpose set forth.

9. A belt-tightener, consisting of the following elements in combination, to wit: two ratchet-bars having tapering slots at the ends; two movable bars having slots at the ends; two operating-levers with attached pawls; and two pairs of clamping-bars adapted to 110 fit the slots in the ends of the ratchet-bars and movable bars; substantially as and for the purpose set forth.
